UNITED STATES PATENT OFFICE

ADELBERT C. MABY, OF RICHMOND HILL, NEW YORK, ASSIGNOR TO THE TABULATING MACHINE COMPANY, OF ENDICOTT, NEW YORK, A CORPORATION OF NEW JERSEY

MOTOR DRIVEN PUNCH

Application filed June 13, 1925. Serial No. 36,798.

This invention relates to card perforating or punching machines adapted for use in connection with the perforated card tabulating art. In this art, data is applied to record cards by perforating the card in certain positions. The perforations in the card are sensed by tabulating machines and the data is then printed and accumulated.

In the co-pending application, Serial No. 10 2,552 filed by J. T. Schaaff on January 15th, 1925 for electric key punch, a perforating machine is disclosed wherein the operator, instead of depressing the keys to manually force the punches through the card, depresses 15 the keys for selecting the punch for operation and for at the same time closing an electric circuit through an electro-magnet. The energization of the magnet then operates the selected punch to perforate the card.

20 In the present invention I have provided an electric motor which may be in constant rotation while the punch is being used. This motor operates an actuator which when a punch-selecting key is depressed quickly actuates the punch, after which the parts immediately return to normal position, leaving the machine in readiness for the next key depression.

One of the objects of the present invention 25 is to devise a punching machine in which greater power is available for forcing the punch through the card so that it may be possible to perforate several cards at once.

Another object is to provide a machine 30 which may be operated with greater speed than is at present possible.

In the aforesaid co-pending application, when a key is depressed a locking device prevents depression of any other key until the 35 depressed key has returned to normal position. In the present invention when a key is depressed and the motor forces the punch through the card the locking device immediately 40 releases the parts so that the next key may then be depressed before the previously depressed key has returned to normal position. This permits greater speed in operation.

45 Referring to the drawings wherein I have

shown what I now consider to be the preferred form of my invention:

Fig. 1 is a front sectional view of a portion of a perforating machine embodying my invention.

55 Fig. 2 is a sectional detail of the punch selecting and operating elements.

Fig. 3 is a sectional view taken on line 3—3 of Figs. 1 and 2.

Fig. 4 is a sectional detail of the driving 60 mechanism taken on line 4—4 of Fig. 3.

Fig. 5 is a sectional detail showing the positions of the parts immediately after the operation of the punch.

Fig. 6 is a fragmentary detail showing a 65 modification in the punch selecting mechanism.

Fig. 7 is a fragmentary detail of the driving mechanism.

In the drawings the machine is shown as 70 comprising a base portion 1 along which a card 2 is adapted to be fed beneath a row of punches 3. The means for feeding the card may be similar to that shown in the aforesaid Schaaff application and will, therefore, not be disclosed in detail here, it being sufficient to point out that the spring driving gear 4 meshes with the rack 5 which is provided with ratchet teeth 6 cooperating with the escapement pawls 7 and 8. The punches 80

3 are mounted in an upper guide support 9 and lower guide 10 and are adapted to be depressed into the die member 11, the card 2 being in position between the members 10 and 11. The punches are provided with 85 springs 12 for returning them to normal position after they have been depressed. Above each punch is an interposer bar 13 guided at the left hand end by a member 14 and at the right hand end by a member 15. Each inter- 90 poser 13 carries a pivoted bracket 16 held by a spring 17 normally in the position shown in Fig. 1 with the lateral stop 18 resting on the top of the interposer. A bell crank 19 pivoted at 20 to the upper casing 21 of the 95 machine is adapted to be actuated by depression of the key 22, a spring 23 being provided to return the key to normal position. A spring 24 connected to the member 15 and to the interposer 13 is adapted to normally 100

hold the interposer in its normally inoperative position toward the right as shown in Fig. 1, also holding the left hand end of the interposer in its upper position against the 5 guide 14. Adjacent to the ends of the several interposers 13 is an actuating ratchet bar 25 having projections 26. The said bar is provided with a shaft 27 fixed thereto. The said shaft is mounted in bearings 28 10 for rotation and is provided with a worm wheel 29 meshing with a spiral gear 30 mounted on shaft 31. Said shaft in turn has a worm wheel 32 meshing with a worm 33 on the shaft of the driving motor 34. When 15 the machine is being used the motor is in constant operation and causes the bar 25 to rotate. When any one of the keys 22 is depressed it moves the corresponding interposer bar 13 from the position shown in 20 Fig. 1 to that of Fig. 2, thus moving the interposer into cooperation with the actuating bar 25. The bar 25 thus depresses the interposer 13 and this in turn depresses the punch 3 to perforate the card. When the 25 interposer 13 is depressed its bracket 16 is carried below the contacting point of the bell crank 19 so that the interposer will then be free to return to normal position under the influence of spring 24. A cam 35 which 30 is here shown as being integral with the punch guide 9 may also be provided so that when the actuator 25 depresses the interposer the latter will engage the cam and be positively withdrawn from the actuator. 35 The cam, however, is not essential. At the right hand end of the interposers are shown the inter-locking elements 36 which prevent more than one interposer moving to operative position at a time. As soon as the bracket 40 16 escapes from the bell crank 19, permitting the interposer to be returned to normal position as shown in Fig. 5, the inter-locking elements 36 are then in position to permit another interposer to be actuated before the key 45 22 has returned to its upper or normal position. Thus when an operator depresses a key he is able to quickly depress the next key without waiting for the previously depressed key to reach its normal position. 50 In Fig. 6 I have shown a modified connection between the operating key 22 and the interposer bar 13. In this form, instead of the spring pressed bracket 16, I have shown a fixed pin 16a. Also the bell crank 19a in this 55 instance is connected to the frame 40 by means of a pin and slot connection 41 to the bracket 42. A spring 43 normally holds the bell crank in its lowermost position. When the key 22 is depressed the bell crank 19a engages the pin 16a and moves the interposer 13 to the left as in the case disclosed in Fig. 2. When the interposer is depressed so that the pin 16a moves out of cooperation with the bell crank 19a the interposer is carried back to normal 60 position as shown in Fig. 6. The parts are 65

then in the position indicated in this view. Now when the key 22 is released its spring 44 returns it to normal position. The bell crank 19a then rides over the top of the pin 16a, the spring 43 permitting the bell crank to rise on its pin and slot connection 41 until it passes over the pin 16a and drops down into position ready to be operated again. The spring 44 is stronger than spring 43 and also has a much greater leverage in acting upon the 70 bell crank 19a so that there is no difficulty in forcing the spring 43 to yield to permit the bell crank 19a to ride over the pin 16a.

In Fig. 7 I have shown a modified connection between the actuating bar 25 and the motor 34. In this case the worm 33 on the shaft of the motor is connected directly to the worm wheel 29 on the shaft 27 of operating bar 25. In this instance the motor is placed directly 80 behind the machine, whereas in the form 85 shown in Figs. 1 and 4 the motor may be placed in the base of the machine.

As shown in Figs. 1 and 2 the carriage escapement pawls 7 and 8 are adapted to be actuated whenever any one of the keys is operated by means of the bail 45. This bail is mounted below the several interposers 13 so that whenever any one of them is depressed the bail 45 is rocked and permits the escapement mechanism to operate to feed the card 95 one step to the left in the manner disclosed in the aforesaid co-pending application.

Having described my invention, what I claim and desire to secure by Letters Patent is:

1. In a record-perforating machine, a punch for perforating a record, a substantially slidably guided bar freely, slidably, engageable with said punch, an actuator for said bar, means for moving said bar into cooperation with said actuator, said actuator being operable to move said bar out of cooperation with said moving means and means for restoring said bar to normal position.

2. In a record-perforating machine, a punch, an elongated bar adapted to operate said punch, means for moving said bar forwardly in the direction of its length to operative position, means for disconnecting said bar from said moving means and means for moving said bar rearwardly in the direction of its length while being so disconnected.

3. In a record perforating machine, punching elements, a constantly running actuator, an interposer member for each element, means for selectively actuating said members to operative position for correspondingly selectively connecting the actuator to the punches, means effective by actuation of one interposer member for preventing actuation of another interposer member and means for releasing such other interposer member for operation independently of the position of said selective means.

4. In a record perforating machine, punch-

ing elements, an operating member for each element, keys for selectively actuating said members to operative position, means for preventing actuation of more than one member at a time, and means for permitting operation of any key before the previously operated key has returned to original inactive position.

5. In a punching machine, a plurality of punches, a common actuator therefor, means in engagement with the punches for coupling said actuator to said punches, means for selectively moving said coupling means into engagement with said actuator to effect coupling, and means operating while punching is being effected for returning said coupling means to normal ineffective position.

10. In a perforating machine, a frame, punches carried thereby, bars, each bar co-operating with a corresponding one of the punches, a constantly running actuator for operating said bars to cause operation of the corresponding punches, and cam means on said frame adjacent the punches for releasing 15 the operated bars from the actuator.

15. In a record perforating machine, a punch element, an elongated bar associated therewith, actuating means for the bar, a selector for moving the bar in one direction 20 into cooperation with the actuating means, the latter thereupon moving the bar in a direction transverse to the length of the bar to effect operation of the punch element, and means for moving the bar opposite to the 25 first-named direction simultaneously with its movement in the second-named direction.

20. In a record perforating machine, a punch element, an elongated bar associated therewith, actuating means for the bar, a selector for moving the bar forwardly in the direction of its length into cooperation with the actuating means, and means for automatically moving the bar rearwardly in the direction of its length each time it is actuated by said actuating means and while said actuation is taking place.

In testimony whereof I hereto affix my signature.

ADELBERT C. MABY.
